THURBER'S DESIGN FOR ANTI-FRICTION METAL IN 3

Theodore Thurber of Auburn, New York.

DES. 1938

Letters Patent No. 1938-Dated April 26, 1864.

Design for a Trademark.

The schedule referred to in these Letters Patent and making part of the same.

To all whom it may concern:

Be it known that I, Theodore Thurber of the City of Auburn, in the County of Cayuga and State of New York, have produced a new and original design for a trade mark: and the following is a full and exact description of the same, reference being had to the accompanying drawings, making a part of this specification.

Fig. 1. represents the motto, in the tablet with the No. 1 quality of the metal, and the device to correspond with it.

Fig. 2. represents the same tablet, with the No. 2 , and the device to correspond.

Fig. 3. shows the same, with the No. 3 .

Fig. 4. (ib) - No. 4 .

The design consists in a tablet of lines or bars on each side surrounding the words composing the motto, together with the device and the dividing bar at the right hand end in which to insert the numbers, as No. 1 , No. 2 , No. 3 , and so on in combination with the device at the left hand end of the motto which is a $\times$ connected with a bar, and short bars or dash $-$, $=$, in the number to correspond with the No. 1 , or No. 2 , or No. 3 , at the right hand end. At the left hand end of the motto, is my peculiar device, or trademark, which consists of connecting the two parallel lines a. a. together by short angular lines e. e., crossing each other, the outer

DES. 1938

2 ends being connected together by a cross bar at the left of which are longitudinal lines or dashes e. e. e. the number of which are made to correspond with the numbers at the right hand end of the motto which indicates the quality of the metal. Thus in Fig. 1 No. 1, there will be only one short line or dash ( ) at the left hand end. In Fig. 2 No. 2 there will be two of the dashes ( ) parallel with each other and in Fig. 3 No. 3, there will be three of the short lines or dashes ( ) and so on for every grade and quality of the metal, that is pre-
pared and sold - which is sanctioned by me for the purposes for which I have discovered its applicability and utility.

Having thus fully described my device, motto, and trade mark, what I claim as a design, and desire to secure by Letters Patent, is -
The design for a trade mark as shown and described.
